UNITED STATES PATENT OFFICE.

ROBERT ALEXANDER STURGEON, OF PORTSMOUTH, ENGLAND, ASSIGNOR TO VICKERS LIMITED, OF WESTMINSTER, ENGLAND.

SUBMARINE MINE, DEPTH CHARGE, AND OTHER EXPLOSIVE BODIES FOR SUBMARINE USE.

Application filed August 31, 1921. Serial No. 497,292.

(GRANTED UNDER THE PROVISIONS OF THE ACT OF MARCH 3, 1921, 41 STAT. L., 1313.)

To all whom it may concern:

Be it known that I, ROBERT ALEXANDER STURGEON, a subject of the King of Great Britain, residing at H. M. S. Vernon, Portsmouth, England, have invented certain new and useful Improvements in and Relating to Submarine Mines, Depth Charges, and Other Explosive Bodies for Submarine Use (for which I have made application in Great Britain January 30, 1917), of which the following is a specification.

This invention relates to that class of body charged with explosive to which the term depth charge has been applied, and the function of which hitherto has been to fire automatically on reaching a predetermined depth.

Heretofore this class of body has generally been designed to fire at a predetermined depth governed by a hydrostatically operated firing mechanism in which the water pressure at a given depth on a given area overcomes the resistance of a spring.

The object of the present invention is the provision of an automatic firing mechanism in which firing takes place after a time interval dependent on the rate of filling, and not dependent on the external pressure of water.

According to this invention automatic firing of a depth charge is governed by a timing device, dependent on the rate at which water can enter through an adjustable inlet to a chamber, the arrangement being such that the time taken to fill the chamber to the required extent by the continuous admission of water through the inlet, due to the immersion of the body in water, is equal or substantially equal to the time the body will take to sink freely to the specified depth. When sufficient water has entered the chamber the pressure produced therein operates the firing mechanism, this internal pressure being independent of the external pressure of the water. By this means should a depth charge be dropped into a depth of water less than the selected firing depth, it will remain on the bottom for a certain period, and will then be fired automatically, on the aforesaid chamber filling to the required extent.

According to one construction the firing

mechanism operated is the hydrostat of any pressure operated firing gear suitable for this class of weapon, the hydrostat being arranged in a chamber into which water can enter at any desired rate by means of one or more inlet holes, the rate of admission of water being governed so that the time taken for the chamber to fill to the required extent if continually sinking is practically the same as that for the body to sink freely to the specified depth. If before reaching this specified depth the body should be brought to rest in any way, the chamber will go on filling, and when the required amount has been admitted, this will automatically operate the firing mechanism.

Obviously the external water pressure must be at least as great as that required to fire the pressure operated firing gear provided.

The diaphragm or other moving member of the hydrostat employed for the purpose of firing the pressure operated firing gear is substantially for the purpose of providing a water tight connection between the parts and any required movement to fire the detonator, such as for example, the compression of a spring or air, or to bring electric contacts into engagement.

A constructional form of device for enabling the invention to be carried out in practice is illustrated in the accompanying drawings in which Figure 1 is a sectional elevation showing in full line the mechanism for allowing the water to enter and governing the rate of admission thereof, while the chamber into which the water passes is shown in dotted line, this chamber being adapted to be connected to the water side of the hydrostatically operated device. Figure 2 is an end elevation at the right hand side of Figure 1. Figure 3 is an end elevation of the cover plate of the device. Figure 4 is an end elevation of the inner face of the said cover plate, and Figures 5 and 6 are elevation at right angles of details of Figure 1.

The mine, depth charge or the like is provided with a chamber 1 in or adjacent to which a diaphragm or movable member of a hydrostat is mounted so as to be displaceable under pressure of water admitted to

the chamber. One side of the chamber is bored and shaped to receive a depth adjuster or water admission valve which fulfills the dual purpose of regulating the depths of times at which the charge will be fired automatically after launching and of providing a safety means to prevent accidental firing.

The valve body 2 is provided with a bore 3 to receive a spindle 4 and other parts 10 hereinafter described, the spindle being shown separately in Figure 5 and having on its inner end a square on which is keyed a locking plate 5 shaped as shown in Figure 2, to act as a safety device for the pressure 15 operated firing gear a collar 6 on an extension 7 of which is engaged by one of the arms 8 of the plate when the safety device is in operation. When the safety device is out of operation, the collar 6 can travel in the 20 recess between two adjacent arms 8.

Between the ends of the spindle is mounted a valve plate 9 which is shown detached in Figure 6 and is provided with four holes of different diameter. Obviously the 25 number of holes provided will depend upon the number of variations in depth or time of firing desired in general four would be sufficient. The inner face of the valve plate is ground into its setting 10 formed by the 30 wall of the body 2, the wall being provided with an aperture 11 to lead water passing through the hole in the valve plate into the chamber 1.

The outer end of the spindle is provided 35 with a feather or key 12 on which is slidably mounted a disk or washer 13 between which and the valve plate a spring 14 is mounted on the spindle. The washer is preferably provided with ribs 15 for the 40 purpose hereinafter described.

The valve body 2 between the normal positions on the valve plate and the washer is provided with apertures 16 covered with gauze 17 to prevent entrance of solid matter which may be floating in the surrounding water.

The valve body 2 is provided with a cover plate 18 formed with a circular opening out of which two sets of radial slots 50 19, 20 are cut, and the purpose of which will be hereinafter described.

The outer end of the spindle 4 is provided with a removable key 21 the inner end of which is provided with one or more 55 studs 22 arranged to be on the inner side of the cover plate 18, the key being provided with a pointer or indicator 23 arranged to be on the outside of the cover plate.

60 The slots 19 are for the purpose of inserting or withdrawing the key 21 with respect to the spindle 4, when any of the holes in the valve plate 9 is over the hole 11 in the valve body, while the slots 20 are for the 65 purpose either of receiving the ribs 15 of

the washer 13 when the key is withdrawn from the spindle 4 and so prevent any further rotation of the valve plate 9 or of receiving the studs 22 of the key, when it is in a position corresponding to safe, thereby retaining the locking plate 5 in the safe position relatively to the collar 6 above referred to, the key and its studs being kept in the safety position by the spring 14 and the pointer 23 will be registering with a position marked safe on the outside of the cover plate 18.

On the key being forced inwards to bring the studs 22 away from the safety recesses 20, the key and the spindle can be rotated and consequently the valve plate 9 to bring the desired hole in this plate to register with the aperture 11 in the valve body and at the same time to bring the space between the arms 8 of the locking plate 5 into line with the collar 6 above referred to to allow free movement of the extension 7 of the pressure operated firing gear mechanism. The pointer 23 will show in the cover plate 18 what adjustment has been made. On the key being released the spring 14 forces it and the washer 13 outwards, whereupon the studs 22 will be registering with the slots 19 and the ribs 15 will be engaging in the slots 20. The key can then be drawn off the spindle 4 and no further accidental rotation of the spindle 4 can take place.

If another depth or time adjustment is now required or for some reason it is now desired to place the firing gear at safe the key is inserted on the spindle 4 and the operations above described performed, it being observed that with the construction above described a safe position is always passed through between two adjacent firing 105 positions.

As the key can only be removed when the device has become set for firing, the delivery up of the key is proof that the charge has been launched in a ready condition.

Instead of a perforated valve plate of the kind above described, a construction may be employed in which the valve has a member with a port co-operating with another member having a succession of holes of the same or different sizes the two members being relatively adjusted to allow the desired number of holes to be in register with the port. Each setting thus has one or more holes exposed instead of single holes of different sizes as above described.

What I claim and desire to secure by Letters Patent of the United States is:—

1. A depth charge comprising a chamber 125 which acts as an air lock and which is formed with a water inlet opening, pressure operated firing mechanism within said chamber, and means for varying the rate at which water is allowed to enter said 130

- chamber so that the time taken to admit sufficient water to the chamber to build up therein sufficient pressure to operate the firing mechanism is equal to or substantially equal to the time taken by the depth charge to sink freely to a specified depth, said operating pressure inside the chamber being independent of the hydrostatic pressure prevailing outside the depth charge.
- 5 2. A depth charge comprising a chamber acting as an air lock and formed with a water inlet opening as claimed in claim 1 and rotatable means for varying the cross-sectional area of said opening so as to govern at will the rate of entry of water to said chamber so as to vary the time taken to build up within the chamber the internal pressure necessary to operate the firing mechanism.
- 10 3. A depth charge, comprising a chamber formed with a water inlet opening, pressure actuated firing mechanism within said chamber and a rotatable obturator, controlling the cross-sectional area of said opening, 25 said obturator being formed with a plurality of openings any one of which can be brought into register with the opening in said chamber so as to admit water at a predetermined rate to said chamber.
- 20 4. A depth charge, comprising a chamber formed with a water inlet opening, pressure actuated firing mechanism within said chamber, a rotatable plate formed with a plurality of apertures of different cross-sectional area and means for bringing any one of said apertures into register with the opening in said chamber for the purpose specified.
- 25 5. A depth charge comprising a chamber acting as an air lock and formed with a water inlet opening as claimed in claim 1, pressure actuated firing mechanism within said chamber, a rotatable plate formed with a plurality of apertures of different cross-sectional area and a detachable key for engaging with and rotating said plate so as to bring any one of said apertures into register with the opening in said chamber for the purpose specified.
- 30 6. A depth charge comprising a chamber formed with a water inlet opening, pressure actuated firing mechanism located within said chamber, a rotatable plate formed with apertures of different cross-sectional areas 35 any one of which can be brought into register with the opening in said chamber and a safety device which prevents movement of said pressure actuated firing mechanism until one or other of the apertures in said plate are in register with the opening leading to said chamber.
- 40 7. A depth charge or like device comprising a chamber formed with a water inlet opening, pressure actuated firing mechanism located within said chamber, a rotatable water admission valve which fulfills the dual purpose of regulating the depths or times at which the charge will be fired automatically and a safety valve to prevent accidental firing.
- 45 8. A depth charge comprising a chamber, pressure operated firing mechanism located within said chamber, valve means for admitting water to said chamber in such manner that actuation of the firing mechanism takes place after a time interval which depends on the rate of filling of said chamber and not upon the external pressure of the water outside said chamber, a detachable handle for setting said valve means, and a safety device for preventing the removal of said handle unless the valve means have been set in correct operative position.
- 50 9. A depth charge as claimed in claim 1 comprising a chamber acting as an air lock, pressure operated firing mechanism located within said chamber, and a rotatable valve controlling an opening in said chamber in such manner that the time taken to fill the chamber to the required extent through said opening is equal to or substantially equal to the time the body takes to sink freely to the depth for which firing has been arranged for in advance.
- 55 10. A depth charge comprising a chamber acting as an air lock and formed with a water inlet opening as claimed in claim 1, pressure operated firing mechanism located within said chamber, a rotatable valve, means for varying the rate of admission of water to said chamber, and a detachable handle for operating said valve.
- 60 11. A depth charge comprising a chamber acting as an air lock and formed with a water inlet opening as claimed in claim 1, pressure operated mechanism located within said chamber, a rotatable valve, means for varying the rate of admission of water to said chamber, a detachable handle for operating said valve means, and a calibrating device over which a pointer on said handle is adapted to move.
- 65 12. A depth charge comprising a chamber formed with a water inlet opening, pressure actuated firing mechanism within said chamber, a valve body located above said chamber, a valve constituted by a rotatable plate formed with a plurality of apertures of different cross-sectional area, mounted within said valve body, a spindle on said plate, a detachable key for engaging with said spindle and rotating said plate, said key being formed with radial extensions, a 70 slideable collar upon said spindle, said collar being formed with upstanding flanges which engage recesses in the valve body, radial slots in the valve body through which the extension in said key is adapted to be passed, and a spring normally tending to maintain the flanges on said collar in en-
- 75 70 80 85 90 95 100 105 110 115 120 125 130

gagement with the recesses in the valve body for the purpose specified.

13. A depth charge as claimed in claim 12 provided with a safety device connected to an extension of said valve spindle, the safety device being provided with radial arms which normally prevent movement of the pressure operated mechanism unless and until one or other of the apertures in said ro-

tatable plate are in correct register with the opening leading to said chamber.

14. A depth charge as claimed in claim 12 in which the detachable key is formed with a pointer and in which calibrations are provided upon the upper face of the valve body for the purpose specified.

ROBERT ALEXANDER STURGEON.
